UNITED STATES PATENT OFFICE

RICHARD STRESAU, OF WAUWATOSA, WISCONSIN, ASSIGNOR TO SWIFTON MANUFACTURING COMPANY, OF WEST ALLIS, WISCONSIN, A CORPORATION OF WISCONSIN

CONVEYER

Application filed May 15, 1929. Serial No. 363,273.

The invention relates to conveyers.

The object of the invention is to provide a conveyer of the endless carrier type in which the supports of the carrier are so constructed and arranged as to allow the endless carrier member to extend the full width of the supporting rollers without employing overhanging or outboard bearings for the roller shafts.

A further object of the invention is to provide a conveyer in which the belt or conveyer-carrying rollers are formed in sections and the bearings for the shafts of said rollers are mounted within the confines of the sections of said rollers.

15 The invention further consists in the combination and arrangement of parts of the conveyer as hereinafter described and more particularly defined by claims at the conclusion hereof.

20 In the drawings Fig. 1 is a vertical sectional view through a conveyer embodying the invention, taken on the line 1—1 of Fig. 2;

Fig. 2 is a horizontal sectional view of the conveyer, taken on the line 2—2 of Fig. 1;

25 Fig. 3 is a detail end view of the conveyer.

Referring to the drawings, the numeral 4 designates a supporting frame and 5 the conveyer frame.

The frame 5 includes side channel iron 30 frame members 6 and transversely extending channel iron frame members 7 which may be connected to the side members 6 by angles 8 that may be riveted or bolted to these parts, or said members 7 may be secured to the side members by welding.

40 A transversely extending shaft bearing support 9, here shown in the form of a bar or shaft, is secured to the conveyer or frame in any suitable manner, as by the threaded ends 10 passing through openings in the side frame members and provided with shoulders 11 held in clamping engagement with said members by nuts 12.

45 Spaced bearing brackets or supports 13 are welded to the support 9 and extend laterally therefrom and are provided with casing portions 14 in which ball-bearing journals 15 are mounted and whose outer races are held 50 therein between the flanged ends of said cas-

ings and plates 16 secured to said casings by screws 17.

A roller supporting shaft 18 is keyed to the inner races of the journals 15 and has roller sections 19, 20 and 21 keyed thereto, the intermediate sections 21 being spaced from the end sections 19 and 21 a distance to admit the arm portions of the brackets 13 therebetween the sections being flanged to provide spaces in which the casing portions 14 are housed. 55 The shaft 18 may be driven in any suitable manner, as by providing a drive extension, here shown as equipped with a pulley 22 for belt connection with a suitable source of power.

60 A shaft 23 is welded or otherwise suitably secured to side plates 24 slidably mounted in the side channels and reinforced by a transverse tie bar 25. The shaft 23 has spaced bearing brackets 26 welded thereto which, 65 similar to the brackets 13, extend laterally therefrom and carry roller bearings 27 in which a roller shaft 28 is mounted.

65 The shaft 28 has roller sections 29, 30 and 31 keyed thereto, the intermediate section 30 being spaced from the end sections 29 and 31 a distance to admit the arm portions of the brackets 26 therebetween, the sections being flanged to provide spaces in which the journal bearings are housed.

70 An endless conveyer 32, here shown in the form of a belt, runs over the supporting rollers and its tension is adjusted by the adjustment of the sliding frame which carries the shaft 23. For this purpose the ends 33 of 75 said shaft 23 are threaded and have angled lugs 34 mounted thereon and secured thereto by nuts 35, said lugs being engaged by bolts 36 mounted in threaded holes in angled lugs 37 welded to the side frame members 4 and 80 adapted to be held in adjusted position by locknuts 38, the screwing in of said bolts causing an outward movement of the shaft 23 and hence an outward movement of the roller structure associated therewith to take up any 85 slack in the belt.

90 While I have shown a belt conveyer and plain rollers it will be understood that other forms of endless conveyers mounted on sectional, revoluble supports, supported in the 95 100

manner heretofore explained, may be used. It will be further noted that this construction eliminated the use of overhanging or out-board bearings for the revoluble supports and makes a compact construction that may be readily applied to different forms of apparatus in connection with which or in which conveyers are used.

I desire it to be understood that this invention is not to be limited to any particular form or arrangement of parts except insofar as such limitations are included in the claims.

What I claim as my invention is:

1. In a conveyer apparatus, the combination of a supporting frame including transverse frame members, laterally extending journal brackets secured to said frame members, shafts journaled in said brackets, sectional cylindrical conveyer supports mounted on said shafts on adjacent sides of said brackets, and a conveyer running over said sectional supports.
2. In a conveyer apparatus, the combination of a supporting frame including transverse frame members, laterally extending journal brackets secured to said frame members and provided with anti-friction bearings, shafts mounted in said bearings, sectional rollers mounted on said shafts and housing said bearings, and a conveyer running over said rollers.

In testimony whereof, I affix my signature.
RICHARD STRESAU.
